[57] CLAIM

The ornamental design for a motorcycle handlebar grip,
as shown and described.

DESCRIPTION

FIG. 1 is a front perspective view of the motorcycle
handlebar grip showing my new design;

FIG. 2 is a rear perspective view thereof;

FIG. 3 is a side elevational view and the rear side elevational
view, top plan view, and bottom plan view would
be a mirror image thereof;

FIG. 4 is a front elevation view thereof; and,

FIG. 5 is a rear elevational view thereof.
